F. A. Richards.*

UNITED STATES PATENT OFFICE.

CHARLES F. DOEBLER, OF HARTFORD, CONNECTICUT.

BRACKET.

SPECIFICATION forming part of Letters Patent No. 595,873, dated December 21, 1897.

Application filed March 10, 1897. Serial No. 626,731. (No model.)

To all whom it may concern:

Be it known that I, CHARLES F. DOEBLER, a citizen of the United States, residing in Hartford, in the county of Hartford and State 5 of Connecticut, have invented certain new and useful Improvements in Brackets, of which the following is a specification.

This invention relates to brackets, it being as to certain of its features an improvement 10 on the bracket disclosed by my concurrently-pending application, Serial No. 621,283, filed January 30, 1897; and it has for its main object the provision of a wall-bracket in which is combined extreme lightness and more than 15 ordinary rigidity and strength, the several parts of which can be readily stamped from sheet metal at a low cost and can be quickly assembled.

In the drawings accompanying and forming 20 part of this specification, Figure 1 is a side elevation of my improved bracket, and Fig. 2 is a front elevation of the same.

Similar characters designate like parts in both figures of the drawings.

25 My improved wall-bracket is preferably constructed entirely of sheet metal, except, of course, the rivets or other fastening devices that hold the respective parts together, and it comprises in its construction a shelf-plate 30 and a wall-plate connected in any suitable manner, but preferably made in one piece, a main brace connecting the shelf and the wall plates, respectively, and an auxiliary brace disposed transversely to the main brace and 35 connecting the latter with the main members of the bracket at the point of intersection of the bracket and wall plates, and strengthening ribs or flanges preferably integral with the main members of the bracket and with 40 the main brace, the latter also having at its opposite ends extended flat portions, which snugly fit against the adjacent faces of the bracket and wall plates, respectively, and have openings registering with corresponding 45 openings in the two plates, through which openings suitable fastening devices may be passed to secure the bracket in position.

The improved bracket is designated in a general way by B, and the shelf and wall 50 plates, which constitute the main members thereof, are denoted by 2 and 3, respectively.

The bracket and wall plates are preferably

formed from a single flat strip of sheet metal bent at the point 4 to form a right angle.

The main brace of the wall-bracket is des- 55 ignated by 5, and it is also preferably of sheet metal and curved between its points of attachment to the main members or bracket and wall plates 2 and 3, respectively, of the bracket, so that by reason of such curvature 60 it is adapted to receive the strain to the best advantage and transmit the same to the auxiliary brace. The main brace 5 is relatively wide, and for the purpose of adding to its stiffness it will be furnished along its oppo- 65 site edges with longitudinal strengthening ribs or flanges 6 and 7, integral therewith and curved for the major part of their length to insure further rigidity. The main brace 5 will be secured to the shelf and wall plates 70 at points relatively remote from their angle, and for this purpose rivets are represented at 8 and 9, the rivet 8 passing through open- 75 ings in the main brace and bracket-plate, re- spectively, and being headed at its upper end, while the rivet 9 passes through similar open- 80 ings in said brace and wall-plate and is like- wise headed.

The auxiliary brace is designated by 10 and is disposed transversely to the main brace 80 and preferably in such a position as to lie in the diagonal line bisecting the angle formed at the junction of the bracket and wall plates, respectively. The auxiliary brace is also stamped from sheet metal and can be made 85 of some fanciful or ornamental design, if de- sired. The auxiliary brace at its opposite ends is beveled off and properly shaped to form 90 projecting lugs 12 and 13, which pass through corresponding holes in the main brace 5 and 3 of the bracket and are headed.

For the purpose of augmenting the stability of the bracket as a whole the main brace 5 thereof will have at its opposite ends 95 the extended flat portions 14 and 15, which snugly fit against the adjacent faces of the bracket and wall plates 2 and 3, respectively, and which project beyond the points of attachment of said brace to the two plates.

The extended portion 14 has an opening 14', which registers with a corresponding open- 100 ing 2' in the bracket-plate 2, and the extended portion 15 has a similar opening 15', which

registers with a corresponding opening 3' near the lower end of the wall-plate 3, and through these several openings suitable fastening devices can be passed to secure the 5 bracket in position, screws being generally employed for the purpose. It will be evident that such fastening devices or screws not only hold the bracket in place but bind the extended flat portions 14 and 15 firmly against 10 the adjacent main members of the bracket.

The strain applied to the wall and shelf plates generally being considerable I provide each of these parts with longitudinal strengthening ribs or flanges, preferably integral 15 therewith and at opposite sides thereof, the ribs of the bracket-plate being designated by 16 and 16' and the ribs of the wall-plate being denoted by 17 and 17', respectively, said ribs being situated intermediate the ends of 20 the respective plates, so that said plates, being, as hereinbefore stated, of sheet metal, are materially strengthened and can better resist the pressures applied thereto. The strengthening-ribs are cut from the body or 25 stock of the main plates 2 and 3 and are bent up therefrom.

Having described my invention, I claim—

A sheet-metal bracket comprising shelf and wall plates in one piece and bent to form an angle, each of said plates having intermediate 30 its ends and at opposite sides thereof longitudinal strengthening-ribs which are cut and bent up from said parts; a main brace secured, respectively, to said plates at points relatively remote from said angle, and curved, 35 said main brace having along its opposite edges longitudinal strengthening-ribs curved for the major part of the length, and also having at its opposite ends extended flat portions which snugly fit against the adjacent 40 faces of the shelf and wall plates, respectively, said extended portions having openings which register with corresponding openings formed in the two plates; and an auxiliary brace transversely disposed to the main 45 brace and having at its opposite ends projecting lugs which pass through openings formed in the main brace and at the angle of the two plates, respectively.

CHARLES F. DOEBLER.
